CLAIM

The ornamental design for a combined bottle and pump head with tamper element, as shown and described.

DESCRIPTION

FIG. 1 is a perspective view of a combined bottle and pump head with tamper element showing our new design;

FIG. 2 is a front view thereof;

FIG. 3 is a rear view thereof;

FIG. 4 is a right side view thereof;

FIG. 5 is a left side view thereof;

FIG. 6 is a top plan view thereof; and,

FIG. 7 is a bottom plan view thereof.

The broken shown illustrate portions of the combined bottle and pump head with tamper element that form no part of the claimed design.

1 Claim, 6 Drawing Sheets
